(57) **CLAIM**

The ornamental design for a golf shoe upper portion, as shown and described.

DESCRIPTION

FIG. 1 is a top perspective view of a golf shoe upper portion showing my new design;

FIG. 2 is a lateral side elevation view thereof;

FIG. 3 is a top plan view thereof;

FIG. 4 is a medial side elevation view thereof;

FIG. 5 is a bottom plan view thereof;

FIG. 6 is a front elevation view thereof; and,

FIG. 7 is a rear elevation view thereof.

The broken lines shown on the top surface of the shoe in FIGS. 1-7 represent thread stitching. The broken lines in FIGS. 1-7 on the bottom of the shoe showing a shoe outsole, including cleats form no part of the claimed design.
